UNITED STATES PATENT OFFICE.

FRANK H. ADAMS, OF CLEVELAND, OHIO.

AUTOMATIC BRAKE MECHANISM FOR PHONOGRAFS.

1,212,872.

Specification of Letters Patent. Patented Jan. 16, 1917.

Application filed January 22, 1915, Serial No. 3,673. Renewed December 1, 1916. Serial No. 134,500.

To all whom it may concern:

Be it known that I, FRANK H. ADAMS, a citizen of the United States, residing at Cleveland, in the county of Cuyahoga and State of Ohio, have invented a certain new and useful Improvement in Automatic Brake Mechanism for Phonographs, of which the following is a full, clear, and exact description.

10 The invention is adjunctive in character and is especially adapted for use in connection with disk phonographs, and may be applied to any disk phonograph without involving any change in any part of said 15 phonograph.

One object of the invention is to provide a cheap and easily applied device which will automatically stop the phonograph when the playing of a record thereby has been completed.

Another object is to provide a stopping device in a form such that it may be easily and quickly adjusted to perform its functions with any record regardless of the distance 25 between the center of the record disk and the point thereon at which the reproducing grooves end.

Another object is to provide a stopping device in a form such that it does not interfere with putting a record on or taking it from the phonograph turntable.

The invention consists in the construction and combination of parts shown in the drawing and hereinafter described and pointed 35 out definitely in the appended claims.

In the drawing, Figure 1 is a plan view of the invention applied to a phonograph; Fig. 2 is a bottom view of the device; Fig. 3 is a vertical section through the outer part 40 of the stop mechanism; and Fig. 4 is an elevation of the device and so much of the phonograph as coöperates therewith.

The application of this invention to, and its use with, any disk phonograph, does not 45 involve any change whatever in the construction of the phonograph itself, although the said invention is caused to be operated by certain parts of said phonograph. The parts of the phonograph which coöperate with this 50 invention include the turntable 3 upon which a disk record 4 may be supported, the tone arm 5 which is mounted to swing freely upon a vertical axis, and some part carried by the tone arm, preferably the needle 6. An arm 55 10 extends horizontally over the turntable and the disk record thereon from one side

to a point beyond the place 4^a at which the reproducing grooves on the disk record will end. A spring-actuated brake lever 12 is pivoted on a vertical pivot adjacent to the 60 edge of the turntable and in such position that when released from restraint the brake lever, actuated by its spring 11, will swing into engagement with the edge of the turntable and thereby apply such braking pressure thereto as will stop its rotation. 65

In the very simple construction shown, the arm 10 and the brake lever 12 are integral with each other and are pivoted to the upper horizontal arm 13 of a bracket 15, which is 70 adapted to be secured to a suitable part of the phonograph case or cabinet. A catch lever 14 is pivoted to the under side of the arm 10. On the outer end of this lever there is a finger 14^a which is adapted to enter a 75 notch 13^a that is formed in the arc-shaped edge of the said arm 13. The arm 10 is provided near its free end with a longitudinal slot 10^a. A stud 16 is slidable in this slot and may be fixed to the arm at any point 80 thereon within its range of travel. In the particular construction shown the part of the stud which passes through this slot is threaded to receive a nut 17. By tightening this nut the stud may be secured to the arm 85 at any desired point thereon. A cam 18 is pivoted to the projecting lower end of the stud, and this cam is always in contact with an edge of the catch lever near the outer end thereof. Fixed to this cam is a trip finger 90 20 which projects into the path of some part of, or attachment to, the swinging tone arm 5. Preferably this finger projects into the path of the needle 6.

The described device operates as follows: 95 When a record disk 4 is being put onto the turntable the arm 10 will be in the position indicated by dotted lines in Fig. 1 which shows a part of said arm. When the record disk is on the turntable the arm will be 100 swung to position shown by full lines in said Fig. 1, that is to say, the position such that it extends over a part of said record disk. When it reaches the required position the catch lever 14 will be moved by the 105 spring 11 so as to push the catch finger 14^a into the notch 13^a and thereby the arm 10 will be held in the stated position. Then the stud 16 will be moved along the arm 10, as required, to bring the end of the trip finger 110 20 directly over a part of the disk record on which the non-reproducing grooves are

2

found. One can readily see when the trip finger has been put in the proper position, because the reproducing grooves on the record present quite a different appearance than the non-reproducing spiral grooves which are formed on each record disk for the needle to travel in after the record has been played. When this trip finger has been properly positioned, the stud may be fixed 5 to the arm 10 by screwing down the nut 17. As the record is being played the tone arm will be gradually swung toward the center of the turntable, the needle 6 traveling in the reproducing spiral grooves of the record. Just as the needle passes out of these 10 reproducing grooves and into the other non-reproducing grooves, it will engage the trip finger 20 and move it so that the cam will move the catch lever 14 and thereby withdraw the catch finger 14^a from the notch 13^a. Immediately thereafter this arm, actuated by its spring 11, will swing toward the 15 position indicated by the dotted lines in Fig. 1; and, of course, the brake lever 12 will also swing until its braking surface engages the periphery of the turntable and stops its rotation.

In the specific construction shown the pivot stud 21 on which the arm 10 is pivoted 20 to the bracket arm 13, extends down a considerable distance; and the spring 11, which is a spiral spring, embraces it and has one end connected with the bracket 15. The other end is bent up so as to engage the edge 25 of lever 14. Therefore, this one spring actuates both the catch lever and the swinging arm 10,—and this because after the spring has moved the catch lever as far as it will go relatively to said arm, it will continue to 30 exert its force on the arm itself.

It is to be understood that the specific construction shown, while the best embodiment 35 of the invention known to me, is merely one specific form of an invention which may be embodied in many different specific forms. The fundamentally novel feature of the invention is the arm which extends over the record and carries a movable trip finger which projects into the path of some part 40 carried by the tone arm of the phonograph, and is adjustable lengthwise of said arm so that it will be engaged and moved with the result of causing the brake to set when the needle reaches any desired part of the record.

Having thus described my invention, what I claim is:—

1. A stopping attachment for disk phonographs of the type having a rotary turntable and pivoted tone arm, comprising in 45 combination a pivoted arm adapted to extend horizontally over a part of a disk upon the phonograph turntable, a spring for swinging said arm away from said position, restraining means preventing the spring-

induced movement of said arm, a brake for stopping the phonograph which is moved in the brake applying direction by the spring-induced movement of said arm, a trip finger carried by said arm and adapted to project into the path of a part of the phonograph which is carried by the tone arm thereof, and means whereby the trip finger by its movement releases said arm from said restraining devices. 70

2. A stopping attachment for disk phonographs of the type having a rotary turntable and pivoted tone arm, comprising in combination a pivoted arm adapted to extend horizontally over a part of a disk upon 80 the phonograph turntable, a spring for swinging said arm away from said position, restraining means preventing such spring induced movement, a brake for stopping the phonograph which is moved in the brake applying direction by the spring induced 85 movement of said arm, a trip finger which is adjustable lengthwise of said arm and adapted to project into the path of a part of the phonograph which is carried by the tone arm thereof, and means whereby the trip finger by its movement releases said arm from said restraining devices. 90

3. A stopping attachment for disk phonographs of the type having a rotary turntable and pivoted tone arm, comprising in combination a pivoted arm adapted to extend horizontally over a part of a disk record upon the phonograph turntable, a bracket arm to which said arm is pivoted, 100 which bracket arm is provided with an arc-shaped edge in which there is a notch, a catch lever pivoted to said arm and having a finger adapted to enter said notch, a cam pivoted to said arm in position to engage with said catch lever, a trip finger connected with said cam and adapted to project into the path of a part of the phonograph which is supported on the swinging tone arm thereof, a spring acting to swing said arm away 110 from its initial position and a brake adapted to be operated by the spring-induced movement of said arm, for stopping the phonograph. 110

4. A stopping attachment for disk phonographs of the type having a rotary turntable and pivoted tone arm, comprising in combination a pivoted arm adapted to extend horizontally over a part of a disk record upon the phonograph turntable, a bracket arm to which said arm is pivoted, which bracket arm is provided with an arc-shaped edge in which there is a notch, a catch lever pivoted to said arm and having a finger adapted to enter said notch, a cam pivoted to said swinging arm on a pivot which is adjustable lengthwise of the arm, a trip finger connected with said cam and adapted to project into the path of a part of the phonograph which is supported on the swinging 120 130

tone arm thereof, a spring acting to swing said arm away from its initial position, and a brake adapted to be operated by the spring induced movement of said arm for stopping the phonograph.

5. A stopping attachment for disk phonographs of the type having a rotary turntable and pivoted tone arm, comprising in combination a pivoted arm adapted to extend horizontally over a part of a disk record upon the phonograph turntable and a brake arm rigidly fastened to said swinging arm, a spring acting upon said arm to swing it away from the position stated and to a position such that the brake arm will engage with the periphery of the turntable, means restraining said arm from moving in the direction which it is impelled to move by said spring, and a trip finger carried by said arm and adapted to project into the path of a part which is carried by the swinging tone arm of the phonograph, and means whereby the movement of said trip finger will disconnect the swinging arm from said restraining devices.

6. A stopping attachment for disk phonographs of the type having a rotary turntable and pivoted tone arm, comprising in combination a fixed bracket adapted to be located outside of said turntable and having a horizontal arm whose edge is arc-shaped and is formed with a notch, a spring actuated arm pivoted to said bracket arm, a brake fixed to said pivoted arm, a spring actuated catch lever mounted on said swinging arm and provided with a finger adapted to enter said notch, a cam stud carried by and adjustable along said swinging arm, a cam pivoted on said stud in position to engage a part of said catch lever, and a trip finger fixed to said cam and extended therefrom to a position such that it may be engaged and operated by some part fixed to the tone arm of the phonograph.

In testimony whereof, I hereunto affix my signature in the presence of two witnesses.

FRANK H. ADAMS.
